AUGER-TYPE DRILL BIT

Orville Phipps, Adams County, near Denver, Colo.

Application October 29, 1946, Serial No. 706,365

1 Claim. (Cl. 255—61)

1

This invention relates to auger-type drills adapted for use in the bore-developing penetration of relatively refractory materials and natural strata, such as rock, coal, mineralized beds, concrete, and the like, and more particularly to bit elements for removable and replaceable association with and as the cutting tips of such augers, and has as an object to provide an improved auger drill bit.

A further object of the invention is to provide an improved construction and arrangement of elements constituting a drill bit for operative association with and to function as the cutting tip of an auger drill.

A further object of the invention is to provide an improved auger drill bit particularly adapted for the efficient development of bores at various angles to the vertical.

A further object of the invention is to provide an improved auger drill bit that is self-piloted for the development of straight bores regardless of bore depth or inclination angle.

A further object of the invention is to provide an improved auger drill bit of enhanced penetrative effect and bore-scavenging characteristic.

A further object of the invention is to provide an improved auger drill bit free from tendency to bind in the bore under development, operatively productive of a smooth right-cylindrical bore of uniform diameter, and cooperative with conventional auger-type drill stock for the rapid and effective clearing of drillings from the bore being drilled.

A further object of the invention is to provide an improved auger drill bit that is simple and inexpensive of manufacture, readily removable and replaceable as the cutting tip of an actuating string or line, characterized by high operative efficiency throughout a long life of practical use, and susceptible of simple and convenient repetitive rehabilitation in the field.

With the foregoing and other objects in view, my invention consists in the construction, arrangement, and combination of elements hereinafter set forth, pointed out in my claims, and illustrated by the accompanying drawing, in which—

Figure 1 is a plan view of the cutting end or face of a typical bit construction embodying the principles of the invention. Figure 2 is a side elevation of the showing according to Figure 1 as operatively associated with a length of conventional auger stock shown in broken lines. Figure 3 is a section longitudinally through the construction according to the preceding figures, taken

2

substantially on the indicated line 3—3 of Figure 1. Figure 4 is a fragmentary, detail section taken through and substantially axially of a centering or pilot element adapted for removal and replacement relative to the bit assembly.

As shown in the drawing, the improved bit is a unitary assembly of elements adapted for removable and replaceable association with and as an outer terminal on a line or section of conventional, spirally-fluted auger stock or stem, illustration of the latter being omitted from the drawing as being, in and of itself, no part of the present invention.

The improved bit has a unitary, homogeneous, body portion 10 formed from any suitable tractable or readily-worked material, such as steel, in any convenient or desired manner, as by means of forging, pressing, rolling, or the like, to present the form and interrelation of constituent elements illustrated and hereinafter specified. A central portion of the body 10 is formed as a generally circular web 10' concentric with the ultimate bit axis, of suitable thickness in the direction of said axis, and preferably conically 15 tapered from an outer greater and toward an inner lesser base. Centrally of the body web lesser base, an integral mounting stem 11, suitably angular in cross section, projects axially of the bit assembly and away from the body web 20 greater base, said stem 11 being sized and shaped to enter and be telescopically received within an end-opening socket formed for such purpose axially of one end of the actuating stem or stock 11' of the conventional drilling apparatus. Any 25 suitable means, such as a hole 12 laterally traversing the stem 11 for registration with correspondingly-located holes in the actuating stem or stock, may be provided to receive means, such as a tapered pin, for separably interlocking the stem 11 and body 10 to and in mounted relation on the end of the associated actuating means. Integral with, uniformly spaced angularly about, and correspondingly disposed relative to the greater base side of the body web, a plurality, in 30 this instance three, of identical fingers 13 project parallel to the axis of the assembly and in a direction opposite to the disposition of the stem 11. Each of the fingers 13 defines an outer edge margin 13a paralleling the assembly axis and at a radial distance therefrom corresponding to the radius of the desired bore, an axially-parallel, substantially-radial plane face 13b perpendicular to the direction of bit rotation and having a width inwardly from said outer edge margin 13a on the order of one-half to three-quarters of the

radius determined by said edge margin, an axially-parallel, inner plane face 13c perpendicular to said substantially-radial face 13b at the inner margin of the latter, and an arcuate outer surface 13d eccentric to the assembly and the desired bore so disposed as to position its margin 13e trailing in the direction of bit rotation more nearly adjacent the bit assembly center than its leading margin 13a. Inner ends of the fingers 13 base solidly in and upstand perpendicularly from the body 10 web portion 10' and arcuate marginal segments of the latter between the trailing margin 13e of one said finger and the leading margin 13a of the next succeeding finger are dubbed away to planes substantially tangent to the leading finger arcuate outer surface 13d at the trailing margin 13e of said finger to provide marginally-open areas through which drillings may freely pass from the working face and to the auger stem when the bit is operating within and for the extension of a bore. Outer ends of the fingers 13 are worked to recede, either arcuately or along a bevel plane, in trailing relation with a forwardly-directed cutting edge margin 13f laterally traversing the radially-disposed, plane forward face 13b of each finger perpendicular to the bit assembly axis, so that the said cutting edge margins 13f of the fingers lie in a common plane defining a working face perpendicular to the drill assembly and bore axis, and corresponding inner corners of said finger outer ends are preferably relieved to inwardly and axially converging surfaces 14 which interrupt the associated finger cutting edge margin 13f for inclination of the inward portion thereof out of the common working face plane at an angle toward the body web 10'.

Power rotation of the bit assembly about its axis with the finger 13 outer ends in pressure engagement against the material to be penetrated is effective through the finger outer end cutting edge margins 13f to develop an annular channel in said material having an outer diameter determined by the spacing of the finger outer edge margins 13a radially of the bit and an inner diameter determined by the radial disposition of the finger inner edge margins determined by intersection of the finger plane faces 13b and 13c, the floor of said channel having an outer annular portion perpendicular to the bore axis and an inner annular portion of outwardly-directed, flat cone form; the eccentric disposition of the finger arcuate exterior surfaces 13d assuring ample clearance for the fingers 13 within the channel cut by the finger working edges 13f and thereby eliminating any tendency of the assembly to bind within the bore. When susceptible of convenient, economical working and forming by conventional tools and methods, the material from which the body 10, shank 11, and fingers 13 is formed will not long successfully resist, no matter how tempered and treated, the abrasive forces tending to deform and wear away the working margins of the bit, particularly when in contact with highly refractory material, hence a significant feature of the invention is the arming of the bit working margins with insert blocks of tough, hard, abrasive-resistant material having a wear characteristic such as will impart long useful life to the bit. Various alloys highly resistant to wear are presently known and available, one of which, in particular, a non-ferrous alloy compounded from tungsten, titanium, tantalum, nickel, and cobalt, has a hardness approaching that of diamond, is exceedingly tough, susceptible of attach-

ment to other metals by means of welding and brazing, and capable of being ground to desired form and shape, hence is well adapted for use to arm the cutting members of the improved bit. 5 Whatever be the material employed for the bit-arming elements, flat blocks 15 of the selected material are provided in a uniform thickness suited to resist the operative stresses contemplated, a width corresponding with or slightly exceeding that of the finger 13 radially-disposed plane faces 13b, and a length on the order of one-half the finger 13 length, one such block 15 being provided for each of the bit fingers 13, and each of said blocks is seated within an angular 10 notch or recess formed for its reception in laterally-traversing relation across and to open through the opposite side margins and outer end of each finger 13 radially-disposed plane face 13b and is therein secured by welding or brazing of its surfaces and margins to the finger 13 material thereby engaged. As mounted and secured in filling relation with its accommodating recess, each block 15 preferably presents a straight inner end based against the recess shoulder along a 15 line perpendicular to the bit assembly axis, a flat face paralleling said axis and leading in the direction of bit rotation, inner and outer side or edge margins smoothly conforming with the adjacent finger 13 surfaces 13c and 13d, and an end or 20 cutting edge margin conforming with the finger outer end leading margin 13f as above described, it being expedient to slightly bevel the working end of each block to provide a forwardly-directed chisel edge productive of advantageous "bite" 25 during operation of the tool, and to slightly bevel or relieve outer corners of the blocks 15, as indicated at 16. As so mounted, the blocks 15 are rigidly affixed to and securely backed by the outer finger 13 portions in position to dispose the block end and side margins as the actual cutting and channel-forming agents of their respective fingers, the special alloy material from which said blocks are formed withstanding operative wear and abrasive effects to maintain the cutting 30 efficiency of the tool and protecting the less resistant metal of the body, shank, and fingers from deforming contact with the material being penetrated, any appreciable wear adversely affecting the cutting efficiency of the block working margins being subject to convenient correction through simple regrinding operations readily accomplished in the field.

As above pointed out, the action of the fingers 13 is productive of an annular channel surrounding and defining a cylindrical core or plug of the material being penetrated, and an operatively significant feature of the invention is the provision of a removably and replaceably associated pilot or centering element axially of the bit assembly for the removal of said core or plug in advance of the said fingers and the development of a short pilot bore centrally of the principal bore face for the centering and guiding of the bit assembly and for facilitation of the work to be done by the finger blocks 15. To mount and operatively relate the pilot or centering element of the invention on and with other elements of the bit assembly, an externally-threaded boss 17 is formed integrally with and to project axially 40 from the greater base area of the body web 10 and hence within and uniformly spaced from each of the group of fingers 13. Removably and replaceably engageable with said boss 17, a cylindrical member 18 is formed to a length materially exceeding that of the fingers 13 from tractable

metal similar to or the same as that used in the body, shank, and finger elements, and to a diameter considerably less than that of the finger 13 inner edge margin orbit but greater than the diameter of the boss 17, so that an internally-threaded axial bore opening through one end of said member 18 may telescopically receive and cooperate with said boss to mount said member to project centrally of the bit assembly within and to extend outwardly beyond the outer end plane of the grouped fingers 13. The end of the member 18 remote from that intersected by its mounting bore is smoothly rounded, or domed, and is diametrically traversed by a relatively-deep, side and end opening slot sized to receive and seat an insert block 19 of special alloy material the same as or similar to that from which the blocks 15 are comprised, said block 19 entirely filling the said member notch and at its inner or base end exceeding in width the diameter of the member 18 to provide wings oppositely projecting radially beyond the adjacent member surfaces a distance significant in operation of the bit and such as will permit free mounting and unmounting rotation of the member within the finger 13 group. The axially-projected outer edge margin of the block 19 is ground to a smooth arc tangent to the member 18 end at the axis of the unit, and inner corners of said block are advantageously inwardly beveled, so that, the pitch direction of the mounting threads being properly related with the direction of bit rotation, actuation of the bit revolves the member 18 about its axis for the development of cutting effect through the block 19 arcuate end and axially-parallel corners and consequent generation of a pilot bore, of a size to freely accommodate the said member, centrally and in advance of the ultimate bore face, such removal of material from the center of the ultimate bore face expediting and very much facilitating the work of the block-armed fingers 13. The axial depth of the block 19 conveniently equals the corresponding dimension of the blocks 15 to provide for repetitious dressing of the various working elements of the tool throughout a uniform useful life, but impairment or abnormally rapid wear of the member 18 working end is of no material consequence in view of the removable and replaceable mounting of said member.

Correlated with and to enhance the action of the drill stem spiral flutings in the removal of chips and drillings from the bore under development, a spiral flange section 20 is formed integrally with and to extend outwardly from an inwardly-extended base of one of the fingers 13 in such position as to register with and complement a screw element of the auger stem whereby with the bit assembly is associated, said section 20 attaining a maximum diameter the same as that of the complementary auger element and being related to the angularity of the bit shank 11 in the same manner as its complementary auger element is related to the angularity of the shank-receiving socket.

Since many changes, variations, and modifications in the specific form, construction, and arrangement, of the elements shown and described

may be had without departing from the spirit of my invention, I wish to be understood as being limited solely by the scope of the appended claim, rather than by any details of the illustrative showing and foregoing description.

I claim as my invention:

In a drill bit of the character described having a body formed with a mounting stem extending axially from one of its sides, fingers integral with and spaced marginally about the side of said body remote from said stem to standout in parallel, radially-offset relation with the body axis and in a direction opposite to the stem extension, insert blocks of hard, tough, abrasive-resistant alloy material, such as tungsten-carbide, fixedly arming the tips of said fingers, and a threaded boss formed integrally with and centrally of said body to standout axially therefrom on the same side of the body as and in spaced, parallel relation with said fingers, a pilot bit member separably carried by said boss, said member comprising a straight, cylindrical, rigid element of a length exceeding the projection of said fingers from the body, a threaded socket coaxially intersecting one end of said element coaxial with and to receive said boss to mount said element on and axially of said body on the same side of the latter as and in spaced parallelism with said fingers, a domed tip defining the end of said element remote from said socket, a slot diametrically of and opening axially of the element through said domed tip, and an insert block of hard, tough, abrasive-resistant alloy material, such as tungsten-carbide, fixedly seated in and to fill said slot with its axially-projected edge tangent to the domed tip at the axis of the element and its opposite side margins similarly projecting laterally of and beyond the element as exposed cutting edges spacedly paralleling the adjacent element wall.
